UNITED STATES PATENT OFFICE

KARL PAULI BILLNER, OF NEW YORK, N. Y., ASSIGNOR TO THE AEROCRETE CORPORATION OF AMERICA, OF NEW YORK, N. Y., A CORPORATION OF DELAWARE

CONCRETE BUILDING CONSTRUCTION

Application filed February 18, 1933. Serial No. 255,358.

This invention relates to building construction and particularly to composite construction such as may be useful in the construction of floors and roofs.

In the building industry at the present time, one of the great demands is for constructions as for floors and roofs which will have great strength both under shearing stresses and under bending moments. The production of light strong constructions saves not only material used but also reduces the weight to be carried which results in ability to build higher buildings on the same foundations or permits of the use of a smaller and less expensive foundation.

The primary object of this invention is the provision of an improved building construction which will combine lightness with strength in building constructions as for example in floors, roofs and bridges and component parts thereof.

Another object of my invention is the provision of an improved building construction wherein the main body of the construction is of some light material, such as cellular concrete, having cells in its structure and at its surface, strips or blocks so combined and reinforced with relation to cross beams of heavy ordinary concrete that a maximum strength for a minimum weight of construction is obtained.

Another object of my invention is the provision of an improved building construction wherein the main body of the floor construction is of plates or beams of light cellular material having cells at its surface, there being supporting portions of concrete, these supporting portions having integral portions between the plates or beams, the surfaces of the cellular material and concrete being joined together by the entry of the cement into the cells of the surface of the cellular material.

Other and further objects of my invention will be apparent to those skilled in the art from a reading of the complete specification and claims.

Referring to the drawings wherein I have illustrated a preferred embodiment of my invention,

Fig. 1 is a cross section of my invention showing the details of construction.

Fig. 2 is a sectional view on the line 2—2 of Fig. 1.

Fig. 3 is a top plan view of a single pre-manufactured beam or strip.

Figs. 4, 5 and 6 are detail views of the reinforcing means.

In the practice of my invention, it is found to be desirable to first construct the supporting members, strips or slabs which are to form the construction. In carrying out my invention, I construct the supporting members 10 at a point distant from the job and haul them to the point where they are to be used. The main body of the supporting members 10 is composed of porous or cellular concrete or other light material having openings on the surfaces into which the regular cement or concrete may enter to form, when hard, a single integral structure. Preferably suitable moulds are provided and the cellular or porous concrete or other liquid substance is poured in. Before this is done, suitable reinforcing means are placed in the moulds.

In the present embodiment of my invention, I have illustrated the supporting member 10 to be used for floor roof or similar construction. Adjacent the place which is to be the bottom of the pre-constructed supporting member 10, I have provided rods 11. These rods 11 extend substantially the length of the supporting members 10 and are turned up to form a U-shaped portion 13.

Centrally adjacent the place to be the top, I have provided a reinforcement 14 of a shape similar to the rods 11 but having the U-shaped portions 15 turned downwardly. The moulds are so shaped that the ends of the supporting members are of a thickness equal to the distance between the points *a* and *b* on Fig. 2. I have found a convenient and efficient form for the end of the supporting members 10 to be as illustrated in Figs. 1 and 3 where the end surface 16 slopes downwardly and away from the center of the member. At substantially right angles to the surface 16 is an under contacting

surface 17 which supports the end of the member 10 in a recess formed in the concrete of the main cross beams to be described.

In order to hold the reinforcing members 11 and 14 of the support member 10 effectively in position during the making of the supporting members 10, I have provided a series of reinforcements 17^a arranged in planes perpendicular to the length of the member as illustrated in Fig. 2. It will be noted that I have shown the surface 17 in such a position that it contacts on the outside of the reinforcing members 11 and 14. The reinforcing members 17^a are placed at such frequent intervals as is found to be desirable and are secured to the reinforcements 11 and 14 by welding or by any suitable method which will insure holding of the rods 11 and 14 in place during manufacture of the supporting members 10. The sides of the supporting member 10 intended to lie next to adjacent supporting members are of special construction. In order to form a locking key space to be filled with concrete, I provide the cut away portion illustrated in Fig. 2. At the lower edge, the face *c* is adjacent to a similar face *c* on the adjacent supporting member 10. Above the face *c* is a slanting face *d* which extends inwardly and upwardly to meet a face *e*. This face *e*, it will be noted, extends upwardly but outwardly so that when the concrete is in place between two supporting members 10, there will be a key action whereby pressure on either member 10 or the key member 18 will be transmitted to the other adjacent members.

The supporting ends of the supporting members are cut away outwardly of a point where they extend into the main cross beams to be described. These cut away portions are formed in the mould and provide substantially parallel surfaces as illustrated at 19 and 20.

In addition to the reinforcements in the supporting members 10, I have provided reinforcements for the concrete 18 in the spaces between the supporting members 10. In the form shown, I provide a reinforcing member 19 for the space between each two supporting members. This reinforcing member 19 extends along adjacent the lower portion of the V-portion of the space between two supporting members 10 and near the ends of the supporting members 10, it extends upwardly and at the ends of the supporting members 10 is adjacent the top. The ends of this reinforcing member extend over and downwardly with upwardly curved portions at the extremities in the spaces between the supporting members of adjacent spans. This is shown in Figs. 1 and 5.

In the building construction, the supporting members are preferably pre-constructed

and hauled to the job. They are then supported in place between the lines to be occupied by the main cross beams 20 in which spaces might be I-beams 21 which will form the main reinforcing portions of the main cross beam when the latter is completed.

After the supporting members are in place the reinforcing members are put in place in the spaces between the supporting members and boxes built around the space to be occupied by the beams 20 and of a shape and design to meet the desired conditions. The concrete is then poured into the boxes and the reinforcing members 19 to form the main cross beams 20 and the key portions 18, preferably in a single piece.

A great advantage of my structure is that light material replaces heavy material where possible while still retaining the heavy material where it is needed.

When the heavy concrete is poured, it enters into the cells of the cellular concrete or other open material used and forms a solid integral concrete structure.

While I have described and illustrated in detail an embodiment of my invention, I desire to have it understood that I do not limit myself to the exact showing and that modifications and changes may be made without departing from the spirit of my invention and within the scope of the appended claims.

Having described my invention, what I claim and desire to secure by Letters Patent is:—

1. A building construction comprising main cross beams provided with recesses, supporting members having ends in the recesses and supported by the cross beams, the supporting members being constructed of cellular concrete and having cut away portions at their sides, and filling means for the cut away portions of adjacent supporting members, a reinforcing means extending adjacent the top of a supporting member and into the filling means on opposite sides of the main cross beam.

2. A building construction comprising main cross beams provided with recesses, supporting members having ends in the recesses and supported by the cross beams, the supporting members being constructed of cellular concrete and having cut away portions at their sides, and filling means for the cut away portions of adjacent supporting members, a reinforcing means extending adjacent the top of a supporting member and into the filling means on opposite sides of the main cross beam, the main body of the cross beams and the filling means being concrete and continuous.

3. A building construction comprising main cross beams provided with recesses, supporting members having ends in the recesses and supported by the cross beams, the mem-

- bers being constructed of cellular concrete and having cut away portions at their sides, and filling means for the cut away portions of adjacent supporting members, a reinforcing means extending adjacent the top of a supporting member and into the filling means on opposite sides of the main cross beam, the cut away portions being of such shape that the filling means forms a key thereby locking adjacent supporting members together. 75
- 10 4. A building construction comprising main cross beams provided with recesses, supporting members having ends in the recesses and each having a main body of cellular concrete and having cut away portions along two sides and having reinforcing members in the lower portion and having reinforcement adjacent the upper surface, filling means for the cut away portions, reinforcing members extending adjacent the top of the main cross beams and extending into the filling means for the cut away portions. 80
- 15 5. A building construction comprising main cross beams provided with recesses, supporting members having ends in the recesses and each having a main body of cellular concrete and having cut away portions along two sides and having reinforcing members within the lower portion and having reinforcement adjacent the upper surface, filling means for the cut away portions, reinforcing members extending adjacent the top of the main cross beams and extending into the filling means for the cut away portions, reinforcing members extending adjacent the top of the main cross beams and extending into the filling means for the cut away portions, the main cross beams having a structural steel reinforcement therewithin. 85
- 20 6. A building construction comprising two cross beams, elongated supporting members of cellular concrete of sufficient length to extend between the two cross beams and having spaces between their adjacent sides, filling means in the spaces and extending around the ends of the supporting members and being integral with the cross beams. 90
- 25 7. A building construction comprising cross beams, elongated supporting members of cellular concrete of sufficient length to extend between the cross beams and having spaces between their adjacent sides, filling means in the spaces and extending to the filling means of adjacent rows and around the ends of the supporting members and reinforcing means extending the length of the filling means. 95
- 30 8. A building construction comprising cross beams, a series of rows of elongated supporting members of cellular concrete of sufficient length to extend between the cross beams and having spaces between their adjacent sides, filling means in the spaces and extending to the filling means of adjacent rows and being integral with the main body of the 100
